CLAIM

The ornamental design for a pocketed index card interface for an electronic personal information manager of a programmed computer system with a display screen, as shown and described.

DESCRIPTION

FIG. 1 is a front elevational view of a pocketed index card interface for an electronic information personal manager of a programmed computer system with a display screen showing a first embodiment of our new design; and,

FIG. 2 is a front elevational view of a second embodiment thereof. The broken-line disclosure of the computer system and display screen in the views is for illustrative purposes only and forms no part of the claimed design.
